PORABLE LAMP

Filed Aug. 8, 1927

Inventor:
Francis C. Kollath.

By
Chester E. Warner.
Attorney.

UNITED STATES PATENT OFFICE

FRANCIS C. KOLLATH, OF CHICAGO, ILLINOIS

PORTABLE LAMP

Application filed August 8, 1927. Serial No. 211,351.

My invention relates to portable lamps, and more especially to that class of lamps commonly known as "hand portables," and adapted particularly for use in garages, factories, etc.

It is common practice to provide a hook on the hand portable for hanging it in any convenient place or on the machinery to be inspected. This hook, however, does not hold the lamp rigidly in the desired position to throw the light to the best advantage. This is especially true around intricate machinery.

Most hand portables are provided with a reflector which makes it especially desirable that the portable should be easily clamped in any desired position.

One of the objects of my invention is to provide a simple and effective means whereby a hand portable may be clamped in any desired position and one in which the clamping means is adjustable with relation to the lamp.

Another object of my invention is to provide a device which is cheap to manufacture, easy to assemble, and of few parts.

Realizing that my invention may be varied in its physical embodiment without departing from the spirit of the invention, I desire it to be understood that the specific construction and form herein shown is to be taken as illustrative and not in a limited sense.

In the accompanying drawings like portions of the device are designated by like characters throughout the several figures.

Figure 1 is a side elevation of my invention used in connection with an ordinary "hand portable" having a wire lamp guard.

Figure 2 is a detail sectional view taken on a line corresponding to line 2-2 of Figure 1.

Figure 3 is a detail sectional view taken on a line corresponding to line 3-3 of Figure 1.

Figure 4 is a detail view of a modified form showing the clamp rigidly connected to the lamp guard.

Figure 5 is a detail sectional view taken on line 5-5 of Figure 4.

Referring now to the drawings in detail, the device as illustrated consists of an ordinary "hand portable" having a handle 1 provided with a suitable socket for holding the lamp 2, which is protected by means of the wire guard 3. The usual reflector 4 is supported in one side of the guard.

A bracket 5 is secured to the wires 6 of the guard 3 by means of the ears 7 which are bent around the wires and pressed securely in place. This bracket is also provided with upturned lugs 8 spaced a short distance apart and having holes 9 thru their upper ends to receive the ball 10 which is in turn secured to the clamping member 11 by means of the rivet 12.

In assembly the lugs 8 will spring apart sufficiently to allow the ball to be inserted between them and in alignment with the holes 9; it is then clamped in position by means of the screw 13.

The clamping member 11 is preferably made of two sheet metal parts 14 and 15 forming integral jaws and handles and pivoted together by means of the rivet 16, the two parts being held in operative position by means of the spring 17.

It will be noted that by means of the ball and socket joint as illustrated the light may be turned to any position desired to suit the convenience of the user, after the device is clamped in position.

It has been found in practice that this construction is very reliable and convenient and does not easily get out of order.

In the modified form shown in Figures 4 and 5 the clamp 11 is secured rigidly to the guard. A sheet metal strip 18 is spot welded to the part 14 of the clamp 11 or may be made integral therewith, this strip is then secured to the wires 6 of the guard 3 by clamping the ends 19 around the wires in the same manner as previously described for the bracket 5.

An ear 20 is also sheared out of the handle member 14 and clamped around the cross wire 21 of the guard, thereby securing the clamp and guard rigidly together.

Having thus fully described my invention,

I claim as new and desire to secure by Letters Patent:

1. A hand portable comprising a means for supporting a lamp, a wire guard around said lamp, a bracket on said guard comprising a single piece of sheet metal having a plurality of down turned ears clamped around the wires of said guard, a pair of oppositely extending ears for clamping a ball, a ball between said ears, means for controlling the friction on said ball, and a clamp mounted on said ball and comprising a pair of integral jaw and handle members, one of said members being secured to said ball.
- 15 2. A hand portable comprising a means for supporting a lamp, a wire guard around said lamp, a bracket on said guard comprising a single piece of sheet metal having outwardly extending ears clamped around the wires of said guard, upwardly extending ears for supporting a clamp, and a clamp supported on said upwardly extending ears.

In witness whereof, I have hereunto subscribed my name.

25 FRANCIS C. KOLLATH.
